UNITED STATES PATENT OFFICE.

EDWIN FREDERICK COMBER, OF SELKIRK, CANADA.

PIPE-WRENCH.

SPECIFICATION forming part of Letters Patent No. 664,625, dated December 25, 1900.

Application filed July 24, 1900. Serial No. 24,657. (No model.)

To all whom it may concern:

Be it known that I, EDWIN FREDERICK COMBER, a subject of the Queen of Great Britain, and a resident of Selkirk, in the Province of 5 Manitoba and Dominion of Canada, have invented a new and Improved Pipe-Wrench, of which the following is a full, clear, and exact description.

The object of the invention is to provide a 10 new and improved pipe-wrench which is simple and durable in construction and arranged to insure a firm gripping of the article and to permit of conveniently engaging the jaws with different-sized pipes.

15 The invention consists of novel features and parts and combinations of the same, as will be fully described hereinafter and then pointed out in the claims.

A practical embodiment of the invention is 20 represented in the accompanying drawings, forming a part of this specification, in which similar characters of reference indicate corresponding parts in all the views.

Figure 1 is a side elevation of the improvement with parts broken out. Fig. 2 is a plan view of the same with parts broken out, and Fig. 3 is a transverse section of the same on the line 3 3 in Fig. 1.

The improved pipe-wrench consists, essentially, of a fixed jaw A and a movable jaw B, pivotally connected at C to the fixed jaw A, as is plainly illustrated in the drawings, the inner or opposite faces of said jaws A and B being V-shaped and serrated, as at A' B', so 35 as to engage the pipe or other article at four points, and thereby insure a firm gripping. The jaw A is provided with a rearwardly-extending arm D, passing through the forked upper end of the jaw B, and on the rear end 40 of said arm is held a pivot E for a cam-lever F, preferably formed with two arms, having their forward ends F' provided with cam-surfaces for engaging the backs B² of the fork members of the jaw B, so that when the cam-lever F is swung in the direction of the arrow a' then said cam-lever, by the cam-surfaces F', presses on the backs B² to carry the jaw B toward the fixed jaw A and firmly grip the pipe or other article.

45 At the inner end of the cam-lever F is arranged a pivot G for a handle H, adapted to

be taken hold of by the operator, said handle H having a transverse slot H', containing a pin I, adapted to engage one of a plurality of recesses F², formed in the pivot end of the 55 cam-lever F. A spring J, held on the handle H, presses the pin in engagement with the corresponding recess F². By the arrangement described the handle H is locked to the lever F by the pin I, so that in working the 60 wrench the operator takes hold of the handle H and swings the same in the direction of the arrow a' to give the desired swinging motion to the cam-lever F and cause the latter to swing the movable jaw B toward the fixed 65 jaw A, as previously explained, and thereby firmly grip the object. By pressing the pin I rearwardly out of engagement with a recess F² and then swinging the handle H on the cam-lever F the operator is enabled to set the 70 handle H at any desired angle relatively to the cam-lever F, and when the desired position is reached the handle and cam-lever are again locked together by the spring-pressed pin I engaging the corresponding recess F². 75

As the wrench is composed of but few parts, it is evident that it can be very cheaply manufactured and is not liable to get out of order.

Having thus fully described my invention, I claim as new and desire to secure by Letters 80 Patent—

1. A pipe-wrench, comprising a fixed jaw having an integral arm extending rearwardly, a movable jaw pivoted on said fixed jaw, a cam-lever fulcrumed on said arm and engaging said movable jaw, to swing the latter toward the fixed jaw and a handle connected with the cam-lever, as set forth. 85

2. A pipe-wrench, comprising a fixed jaw having an integral arm extending rearwardly, 90 a movable jaw pivoted on said fixed jaw, a cam-lever fulcrumed on said arm and engaging said movable jaw, to swing the latter toward the fixed jaw, and a handle fulcrumed on the cam-lever and having an adjustable locking connection with said lever, to actuate the latter, as set forth. 95

3. A wrench, comprising a fixed jaw having at its inner end a rigidly-attached arm, a movable jaw mounted to work in opposition 100 to the fixed jaw, and a cam-lever with means for operating it, the cam-lever being pivoted

on the outer end of the arm of the fixed jaw and extending alongside of said arm to engage the movable jaw.

4. A wrench having two pivotally-connected jaws, a cam-lever, the fulcrum of which is carried by one jaw, and the cam-lever engaging the other jaw, and a handle adjustably attached to the cam-lever.

In testimony whereof I have signed my name to this specification in the presence of two subscribing witnesses.

EDWIN FREDERICK COMBER.
